UNITED STATES PATENT OFFICE.

WILLIAM MAXWELL, OF PITTSBURG, PENNSYLVANIA.

EXTENSION-TRAY.

SPECIFICATION forming part of Letters Patent No. 729,078, dated May 26, 1903.

Application filed July 26, 1902. Serial No. 117,146. (No model.)

To all whom it may concern:

Be it known that I, WILLIAM MAXWELL, a citizen of the United States of America, residing at Pittsburg, in the county of Allegheny and State of Pennsylvania, have invented certain new and useful Improvements in Extension-Trays, of which the following is a specification, reference being had therein to the accompanying drawings.

10 This invention relates to certain new and useful improvements in trays, and relates more particularly to that class used by waiters, servants, and the like.

The object of the present invention is to provide an extension-tray that may be quickly adjusted to accommodate all the articles that are to be carried. Furthermore, great difficulty heretofore has been experienced by waiters and servants to convey a large number of dishes or glasses upon a comparatively small tray, which often results in the breakage of the china and glass and a waste of victuals and beverages. Furthermore, waiters lose considerable time in procuring trays of various sizes to accommodate the articles to be served or returned.

15 It is the principal object of the present invention to effectually overcome all the above-stated difficulties and to provide a tray that 20 may be extended to a position to double its ordinary carrying capacity.

25 The invention further aims to provide a device of this character which will be extremely simple in construction, strong, durable, comparatively inexpensive to manufacture, and highly efficient in its use.

The invention consists in providing a tray with two or more sections, said sections being slidably attached to one another, the bottoms and side flanges of the tray being connected together in a manner that will practically form an air-tight connection, thereby retaining the moisture and drippings upon the tray and prevent the same from soiling the table-cloth or coming in contact with the furniture upon which the tray may rest.

30 A still further object of the invention is to provide two or more sections of the tray with bearing-surfaces that will be upon a common horizontal plane with one another, thereby preventing the tray from tilting, which would otherwise occur.

With the above and other objects in view the invention consists in the novel construction, combination, and arrangement of parts 55 to be hereinafter more fully described, and specifically pointed out in the claims.

In describing the invention in detail reference is had to the accompanying drawings, forming a part of this specification, and 60 wherein like numerals of reference indicate like parts throughout the several views, in which—

Figure 1 is a top plan view of my improved tray. Fig. 2 is a vertical sectional view thereof, taken on the line 2 2 of Fig. 1. Fig. 3 is a transverse longitudinal vertical sectional view taken on the line 3 3 of Fig. 1. Fig. 4 is a transverse sectional view taken on the line 4 4 of Fig. 3 looking in the direction of 70 the arrow.

In the drawings the reference-numerals 1 and 2 represent the slidable sections of the tray, these sections being provided with side flanges 3 and 4, the flanges being curved and 75 turned over and the flanges 3 being adapted to telescope in the flanges 4. The section 2 is also provided with downwardly-extending flanges 5, extending below the bottom. These flanges form a bearing-surface for the section of the tray 2 when it is in an extended position, said bearing-surface being upon a common plane with the bottom of the tray-section 1. A downwardly-extending flange 6 is also formed integral with the tray-section 80 2, and a corresponding flange 7 is formed integral with the tray-section 1, the latter, however, extending upwardly and rests against the under face of the bottom of the tray-section 2. Between these flanges 6 and 7 is interposed a strip of rubber or other suitable material 8, which forms both a buffer-stop when the tray-sections are extended to their maximum degree and a perfectly air-tight connection, which will effectually retain the 85 moisture and drippings upon the tray.

90 Ordinarily the tray is used in its contracted form; but when it is found necessary to increase the carrying capacity of the tray the sections are accordingly adjusted to the extended position.

95 The many other advantages obtained by the use of my improved device will be readily apparent from the foregoing description,

taken in connection with the accompanying drawings.

It will be noted that various changes may be made in the details of construction without departing from the general spirit of my invention.

Having fully described my invention, what I claim as new, and desire to secure by Letters Patent, is—

- 10 1. In an extension-tray, the combination of two telescoping sections, one of the said sections being provided on its end with a downwardly-extending flange, the other of said sections being provided with an upwardly-extending flange, said upwardly-extending flange engaging the bottom of the first-named section, substantially as described.
- 15 2. In a tray, the combination of two telescoping sections, one of the said sections being provided with a downwardly-extending

flange, the lower edge of the said flange being upon a common plane with the bottom of the other of the said sections, substantially as described.

3. In a device of the character described, 25 two tray-sections, one of the said sections being provided with downwardly-extending side and end flanges, the other of the said sections being provided with an upwardly-extending flange, and a strip of rubber interposed between said downwardly-extending end flange and said upwardly-extending flange, for the purpose specified.

In testimony whereof I affix my signature in the presence of two witnesses.

WILLIAM MAXWELL.
